UNITED STATES PATENT OFFICE.

JOHN F. TRITLE, OF SCHENECTADY, NEW YORK, ASSIGNOR TO GENERAL ELECTRIC COMPANY, A CORPORATION OF NEW YORK.

ELECTROMAGNETICALLY-OPERATED SWITCH.

964,711.

Specification of Letters Patent. Patented July 19, 1910.

Application filed July 1, 1908. Serial No. 441,292.

To all whom it may concern:

Be it known that I, JOHN F. TRITLE, a citizen of the United States, residing at Schenectady, county of Schenectady, State 5 of New York, have invented certain new and useful Improvements in Electromagnetically-Operated Switches, of which the following is a specification.

My invention relates to electro-magnetically operated switches, and particularly to that class of switches used for controlling power circuits and commonly known under the name of "contactors".

The particular form of switch illustrated 15 and described in this application is adapted particularly for operation by alternating-current but, as will be obvious to those skilled in the art, it might equally well be adapted for use on direct current.

20 The general object of my invention is to provide a new and improved form of electro-magnetically operated switch which will operate satisfactorily on alternating-current.

25 The particular features of novelty will appear from the following description and the appended claims.

Referring to the drawings, Figure 1 shows in side elevation a switch built in accordance with my invention; Fig. 2 is a bottom plan 30 view thereof; Fig. 3 is a side elevation, partly in section, showing particularly the arrangement of the contact members; and Fig. 4 is a view in the direction of the arrow *a* in Fig. 1 showing the short-circuiting 35 rings mounted in one of the faces of the laminated field frame.

Like parts are referred to throughout the several views by the same reference characters.

40 Referring to the drawings, the main frame upon which the parts of the switch are supported is indicated at 5, its form being clear from the drawings. The frame 5 may conveniently be cast in two parts, 45 between which are clamped an E-shaped field structure built up of laminated iron and indicated at 6. The laminae of the field structure 6 may be secured together by rivets 7, some of which, as shown, pass through 50 the two parts of the frame 5 and help secure them and the E-shaped field structure together. The actuating coil of the switch is shown at 8 surrounding the middle leg of the E-shaped field structure and support-

ed upon extensions 9 which project from the 55 frame 10 secured to the frame 5 by bolts 11.

Pivoted upon a pin 12 which passes through alining holes in the side frame 10 is an armature built up of members 13 and 14, between which is interposed the laminated structure 15 of the form shown, the members 13 and 14 and the laminae being secured together by the rivets 16. The armature is provided with an extending arm 17 in the end of which on the pin 18 are 65 pivoted movable contact members 19 of the form clearly shown in the drawing, said contact members being provided with tips 20 which are preferably removably secured in order that they may be renewed when 70 necessary. The lower ends of the movable contact members 19 are engaged by one end of the springs 23, the other ends of which are secured, as shown, to a pin mounted in lugs 24 extending from the armature near 75 the outer end thereof. The springs 23 tend to rotate the movable contact members 19 in a clockwise direction around the pin 18, this movement being stopped when the armature is in the position shown in Fig. 1 80 by the engagement of a part of each contact member 19 with a portion of the armature, as will be clear from the drawing. The springs 23 also bias the armature in a direction away from the E-shaped field frame 85 and, therefore, assist the opening movement of the switch. Strips of flexible conducting material 26 may be used, as shown, between each movable contact member 19 and a lug 27 on each side of the frame 10 in order to 90 provide a good electrical connection between said contact members and the frame instead of relying altogether upon the pivotal connections between the contact members 19 and the armature and between the 95 armature and the frame.

An arc chute 30, of any suitable form is secured to the frame 10 by bolts 31 as shown. This arc chute, which may be of any suitable insulating and arc-resisting material, may 100 conveniently be made in two parts and between them may be mounted the lower contact members 33 provided with removable contact tips 34 which coöperate with the contact tips 20 on the movable contact members 19. A blow-out coil 35 may be mounted in the top of the arc chute and provided with pole pieces 36 of magnetic material 105

embedded in the outer sides of the arc chute in a manner clear from the drawings. One end of the blow-out coil may be secured to the terminal 37, the other end being electrically connected to the frame 10. The fixed contact member 33 may have electrically connected to it a terminal 38.

Embedded in the end of the outer arm of the E-shaped laminated field structure 10 are short-circuited rings 40 of conducting material, such as copper, as best shown in Figs. 1 and 4. The armature is so arranged, with reference to the E-shaped field structure, and the length of the legs of this structure is such that, when the armature is in the position illustrated in Fig. 3, it will engage the outer leg but not the middle or the inner legs.

In order that after the parts have worn, especially the pin 12 and the holes in the armature and frame through which it passes, the armature may by no possibility come into contact with the middle or the inside leg of the E-shaped structure, pieces 42, 25 L-shaped in cross-section and made of phosphor bronze, or other non-magnetic material, may be clamped to the arms 9 and arranged to project inwardly between the upper face of the armature and the lower face 30 of the middle leg of the E-shaped structure. These pieces 42 positively insure the armature not coming into engagement with any of the legs of the E-shaped field structure except the outer one, thereby removing any 35 chance for "sticking" of the armature due to residual magnetism in the field structure.

The operation of the above described switch will be obvious from the drawings. When the switch is open, as shown in Fig. 40 1, and the coil 8 is energized with alternating-current, the armature will be attracted into the magnetic field established between the ends of the three legs of the E-shaped field structure and the movable contact 45 members will be brought into engagement with the stationary contacts. During the first part of the movement of the armature the contact members 19 will move with it, being held with relation to the armature in 50 the position shown in Fig. 1 by the springs 23. The contact tips 20 and 34 first engage near the outer edges of their coöperating faces and as the armature moves farther the springs 23 are stretched and the contact tips 55 20 are caused to rock and slide slightly upon the tips 34 until the armature has risen to its full extent and the contact tips engage near their inner edges, as shown in Fig. 3. Arcing at the contact tips, therefore, due to 60 completing and interrupting the circuit through them, always takes place near the outer edges of their coöperating faces and the inner portions of the faces will not be scarred by arcing, but it will be maintained 65 smooth and capable of making good elec-

trical contact with one another. When the switch is closed, as shown in Fig. 3, the springs 23 are placed under increased tension and serve to hold the contact tips 20 in engagement with the contact tips 34 under certain pressure, and at the same time act, when the actuating coil 8 is deenergized, to accelerate the movement of the armature away from the E-shaped field structure and expedite the opening of the contacts. The 70 circuit controlled by the switch passes from the terminal 37, through the blow-out coil 35 to the iron frame of the switch, thence through the flexible conductors 26 to the movable contact members 19 and their tips 20 to the tips 34 of the fixed contacts 33, and thence to the terminal 38. The rings 40, embedded in the end of the outer leg of the E-shaped field structure, serve as the short-circuited secondary of a transformer, of 85 which the coil 8 is the primary, and the resultant field through these rings will be out of phase with that in the E-shaped frame outside of the rings. The magnetic field at the end of the outer leg is in this way 90 maintained sufficient to insure the armature engaging the end of the outer leg of the E-shaped structure without chattering as long as the coil 8 is energized. Since the armature engages only with the end of the 95 outer leg of the E-shaped structure there is always a gap in the magnetic circuit through the armature, and the latter will not stick in its raised position after the coil 8 has been deenergized, due to residual magnetism in the laminated E-shaped structure. 100

While I have shown but one form in which my invention may be embodied, I do not wish to be understood as limiting myself thereto, except as called for by the following claims. It is obvious that contactors may be built in this manner with either more or less than two pairs of coöperating contact members, the number of these depending merely upon the current in the circuit 110 which it is desired to control.

What I claim as new and desire to secure by Letters Patent of the United States, is:—

1. In an electromagnetically operated switch, a magnetic field frame, a magnetizing coil arranged in coöperative relation to said frame and serving to produce a magnetic field therethrough, an armature coöperating with said magnet frame and pivoted at one side thereto, a movable contact member pivotally supported on said armature at a point on the other side of the axis of said armature from that portion of the armature which coöperates with the magnet frame, a fixed contact member with which said movable contact member coöperates, and a spring connected between said movable contact member and a point on said armature remote from its axis for yieldingly holding said movable contact member 115 120 125 130

in engagement with said fixed contact member and for biasing said armature in a direction away from engagement with said magnet frame when the armature moves into engagement with said frame.

2. In an electro-magnetically operated switch, a supporting frame, a laminated E-shaped magnetic field structure supported in said frame, a magnetizing coil mounted in said frame and surrounding the middle leg of said E-shaped field structure, a ring of conducting material embedded in the end of one of the legs of said E-shaped field structure, an armature of laminated material pivotally mounted in said supporting frame and arranged to move into and out of

engagement with that arm of said E-shaped field structure having the ring embedded therein, a fixed contact member, a movable contact member pivotally supported by said armature, and a spring for holding said movable contact member in yielding engagement with said fixed contact member when said armature has moved into engagement with said E-shaped frame. 25

In witness whereof, I have hereunto set my hand this 30th day of June, 1908.

JOHN F. TRITTLE.
